HORIZONTAL HONING MACHINE

Harry J. Caldwell, Rockford, Ill., assignor to
 Barnes Drill Company, Rockford, Ill., a corporation of Illinois

Application July 21, 1939, Serial No. 285,751

4 Claims. (Cl. 51—34)

The invention relates to machines for dressing cylindrical surfaces by a honing or lapping operation and more particularly to honing or lapping machines of the horizontal type.

The honing operation involves the relative rotation and simultaneous relative reciprocation of a cylindrical abrasive tool or hone and the work piece. The lapping operation is substantially the same as the honing operation except that the relative rotation of the tool and work is intermittent instead of continuous. The term "honing" as employed hereinafter with reference to the dressing of cylindrical surfaces is intended to embrace both of the above operations.

Horizontal honing machines are commonly employed in dressing the cylindrical surfaces of work pieces which, because of certain characteristics such as substantial length, are most conveniently supported in a horizontal position during the operation. In such machines either the tool or the work may be reciprocated and either or both may be simultaneously rotated to produce the relative movements necessary for the performance of the honing operation.

The relative reciprocation of the tool and the work presents a different problem in machines intended to operate on long work pieces since the reciprocatory stroke must be of sufficient amplitude to traverse the tool from one end of the work piece to the other. As honing is a precision operation, the reciprocation should be extremely smooth and with a minimum of shock or jar at the ends of the stroke. This is to prevent vibration or chattering of the tool which seriously affects the quality of the work and makes it difficult, if not impossible, to obtain the smooth true surface finish and the high degree of accuracy for roundness and straightness demanded in finishing operations of this character.

It has been found in practice that pressure fluid operated means such as hydraulic actuators, of either the rotary or reciprocatory type, are most suitable for effecting the relative reciprocation of the tool and work because of the inherent smoothness of operation and the ease and accuracy with which such actuators can be controlled. The reciprocatory actuators are preferable as they are of simple construction and relatively inexpensive to manufacture and easy to maintain in proper operating condition.

The use of reciprocatory actuators has been limited heretofore to short-stroke honing machines of the vertical type in which the actuator can be coupled directly with the moving part, that is, the reciprocatory head or carriage of the

machine. Direct coupling of the actuator with the head has not worked out in the case of long-stroke honing machines because of the impracticability of incorporating in the machine a reciprocatory actuator capable of providing the wide range of movement required in such machines. Various motion transmitting and amplifying devices have been proposed for use in connection with reciprocatory actuators. Such devices as heretofore constructed, embody gear trains, rack and pinion mechanisms or the like, which are unsuitable for effecting the smooth, shockless reciprocation essential for precision honing.

With the above in view, one object of the present invention is to provide an improved horizontal honing machine embodying novel reciprocating mechanism including a pressure fluid operated actuator of the reciprocatory type and motion transmitting and amplifying means of novel and improved construction capable of effecting smooth, shockless relative reciprocation of the honing tool and the work piece.

Another object is to provide novel motion transmitting and amplifying means adapted to be operated by a reciprocatory actuator and capable of effecting the relative reciprocation of a honing tool and the work piece in a manner suitable for precision honing.

Still another object is to provide an improved pressure fluid actuator of the reciprocatory type capable of imparting uniform movements to the reciprocatory head or carriage of a horizontal honing machine in both its forward and return strokes.

Other objects and advantages of the invention will become apparent from the following detailed description of the preferred embodiment illustrated in the accompanying drawings in which:

Figure 1 is a side elevational view of a horizontal honing machine embodying the features of the invention.

Fig. 2 is a vertical sectional view taken longitudinally of the machine showing details of the mechanism for reciprocating the head or carriage.

Fig. 3 is a transverse sectional view of the machine.

Fig. 4 is a schematic diagram view showing the hydraulic circuits and the relationship of the hydraulic and mechanical elements of the machine.

By way of illustration the invention has been shown and will be described hereinafter as embodied in a machine for honing internal cylindrical surfaces in which the tool is rotated and

reciprocated relative to a stationarily supported work piece. It is to be understood, however, that the invention is readily applicable to other types of honing machines and that various changes and modifications may be made in the form, construction and arrangement of the parts without departing from the spirit and scope of the invention as expressed in the appended claims.

Referring to the drawings, the machine selected to illustrate the invention is of the type intended for honing the internal cylindrical surface of a hollow work piece W such as an elongated tube or cylinder. This operation is performed by means with a cylindrical abrasive tool or hone T which may be of any suitable and well known construction. In this particular machine the work piece W is held stationary while the tool T is rotated and simultaneously reciprocated relative thereto.

As shown in Fig. 1, the machine comprises generally an elongated base consisting of a main section 11 and an outboard section 12 bolted or otherwise secured together in end-to-end relation. The latter section constitutes in the present instance a stationary work support and for this purpose is equipped with suitable fixtures 13 for rigidly holding the work piece W in a substantially horizontal position.

In order to obtain the necessary relative movements of the tool and work under these conditions, the tool T is carried by a reciprocatory support herein shown as a head or carriage 14 arranged to reciprocate on a horizontal guideway extending longitudinally of the main base section 11. The guideway, as herein shown, is formed by suitable guide bars 15 (Fig. 3) mounted in parallel spaced relation on the side walls of the base section and the head is supported thereon by a series of generally spool-shaped rollers 16 journaled on studs projecting from the under side of the machine. The rollers are preferably positioned so as to engage the respective guide bars between their inclined bearing faces and thus serve to hold the head securely against lateral movement relative to the guideway while permitting it to reciprocate freely thereon.

As the tool T must be inserted within the work piece and traversed from one end thereof to the other, it is conveniently mounted on the projecting end of an elongated driver 17 which constitutes, in this instance, an extension of a rotary tool supporting spindle 18. The spindle is journaled on the head 14 for reciprocation therewith and is driven in any suitable manner as by a motor M mounted on the head.

Relative reciprocation of the tool and work is effected in the present instance by reciprocation of the head 14 on its guideway. For this purpose there is installed, preferably within the main base section 11, a pressure fluid operated actuator of the reciprocatory type arranged to drive the head through the medium of motion transmitting and amplifying mechanism of novel and advantageous construction.

The actuator may be of any suitable type but is preferably constructed so that the movements of the reciprocatory part are uniform, that is, the movements are executed at the same speed in both directions. Such movements are obtained in the present instance by a double cylinder arrangement wherein equal active pressure areas are utilized for moving the reciprocatory part in each direction.

Referring more particularly to Fig. 2, the actuator in its preferred form comprises an outer

cylinder 21 disposed within the main base section 11 in a substantially horizontal position with its longitudinal axis generally parallel to the guideway for the head. The opposite ends of the cylinder are closed respectively by cylinder heads 22 and 23, the latter having a central opening for the reception of a cylindrical ram 24 which constitutes the reciprocating part of the actuator. The cylinder 21 is anchored to the machine base as by a pin 25 engaging in an aperture in an extension 26 of the cylinder head 22, the pin acting to support the outer end of the cylinder and to permit limited pivotal movement of the same in a vertical plane for reasons that will appear presently. A cylindrical enlargement 27 on the inner end of the ram constitutes a working piston for the outer cylinder. Suitable packing rings 28 may be fitted in the piston enlargement to prevent leakage of pressure fluid from the outer end of the cylinder to the inner end which, however, is vented in well known manner to take care of drainage.

As herein shown, the ram 24 is of tubular construction and its outer end is closed by a tightly fitted plug 31 to form a second or inner cylinder for the actuator. A cylindrical member 32 rigidly secured at one end to the cylinder head 22 of the outer cylinder and projecting forwardly therefrom so as to telescope into the hollow ram, constitutes a stationary piston for the inner cylinder. These parts are assembled with a tight sliding fit to prevent leakage of pressure fluid from the inner cylinder.

To move the ram inwardly or to the right as viewed in Fig. 2, pressure fluid is introduced into the outer cylinder 21 through a port 33 to act on the rear face of the piston enlargement 27. Movement of the ram in the opposite direction is effected by the introduction of pressure fluid into the inner cylinder to act on the front face of the plug 31 which closes the end of the cylinder. For this purpose the stationary member 32 is formed with a bore 34 communicating at one end with the inner cylinder and at the other end with a port 35 in the cylinder head 22. By suitably proportioning the areas presented by the piston enlargement 27 and the plug 31, the rate of movement of the ram in opposite directions can be accurately controlled. In the present instance these parts are constructed so as to present equal pressure areas and the movements of the ram are therefore executed with the same speed in both the forward and return strokes, equal columns of fluid at the same pressure being supplied in each instance.

Pressure fluid for reciprocating the ram is supplied by a suitable pump P through a suitable pressure fluid circuit such as that illustrated diagrammatically in Fig. 4. As herein shown, the pump is driven by an electric motor M. A reversing valve V of the well known pressure fluid operated type, is interposed in the circuit between the pump and the actuator to control the supply of pressure fluid thereto. When the valve is operated to the position shown in the drawings, it is effective to direct pressure fluid into the outer cylinder 21 and to connect the inner cylinder of the ram 24 with a drain 36 for returning spent pressure fluid to a reservoir or sump R. Under these conditions the ram is moved to the right. When operated to its alternate position the valve V directs pressure fluid into the inner cylinder and connects the outer cylinder to the drain so that the ram is moved in the reverse direction, or to the left. The oper-

ation of the valve **V** is preferably controlled by a pilot valve **V**¹ operated in well known manner by the head **14** in its movements back and forth on the guideway.

The movements of the reciprocating part of the actuator or ram **24** are transmitted to the tool head **14** through a transmission mechanism which additionally acts to amplify these movements. In the particular machine illustrated the transmission mechanism is arranged to double the movement of the ram, that is, the tool head is moved through a stroke of twice the length of the stroke of the ram. This construction permits the use of a cylinder and ram of only one-half the length of the guideway. Apparatus of this size can be conveniently installed in the base of the machine since the over-all length of these elements when fully extended, can be accommodated within the main base section. If desired, of course, a greater degree of amplification may be provided without departing from the principles of the present invention.

The motion transmitting and amplifying mechanism in its preferred form includes an elongated generally rectangular metal frame **41** (Figs. 2 and 3) rigidly connected at one end to the projecting end of the ram **24** and reciprocable therewith. The frame is supported and guided for reciprocation by roller means, herein shown as flanged rollers **42** and **43** operating on spaced parallel rails or bars **44** which form a track extending below and generally parallel to the guideway for the head. The rails may be supported in any suitable manner as by U-shaped supporting members **45** suspended from brackets **46** projecting inwardly from the side walls of the base section **11**. The pivotal mounting of the cylinder **21** permits the rollers to follow irregularities in the track without placing undue strains on the cylinder or associated parts.

As will be seen by reference to Fig. 3, the rollers **42** and **43** are rotatably supported on anti-friction bearings **47** carried on horizontal pins **48** fitted into the side members of the frame **41**. Each of the rollers is formed with a pair of outwardly facing flanges **49** which serve the double purpose of guiding the rollers on the rails **44** and defining a generally V-shaped groove **50** for a flexible traction member such as a wire cable by which the movements of the frame and rollers are transmitted to the tool head.

In the particular machine illustrated, one cable **51** (Figs. 1 and 2) is provided for moving the head forwardly or toward the work piece while a second cable **52** is provided for moving the head back to retracted position. These cables are both anchored to the head and connected respectively to the opposite ends of the base, connection with the head being effected in the present instance by a connecting device **53**. It will be understood, of course, that a single cable may be used if desired, in which case it will be anchored at its mid-point to the head and the respective end sections will function in the same manner as the cables **51** and **52** above described.

The cable **51** is carried forwardly from the head over a sheave **54**, then back over the roller **42** and forwardly again to a suitable connecting device **55** which anchors it to the forward end of the base section **11**. The cable **52** extends rearwardly from the head and passes over a sheave **56**, thence forwardly over the roller **43** and again rearwardly to a tensioning device **57** which anchors it to the rear end of the machine base. It will be understood that the sheaves **54** 75

and **56** are rotatably supported on the base section **11** at opposite ends of the guideway.

The tensioning device **57** acts to maintain the cables **51** and **52** under proper tension at all times to prevent any slack or looseness in these cables which would interfere with the smooth, uniform reciprocation of the tool head. The device, as herein shown, comprises a cylinder **61** rigidly secured at one end to the machine base 10 below the reciprocating actuator. The cylinder is fitted with a piston **62** having a forwardly projecting piston rod **63** to which the end of the cable **52** may be secured in any suitable manner as by a connector **64**.

Pressure fluid introduced into the cylinder **61** through a port **65** in the forward end of the cylinder tends to force the piston rearwardly or to the right as viewed in Fig. 2. The piston thus exerts a pull on the cable **52** in a direction such as to draw the cable **51** taut. This tends to pull the head **14** rearwardly against the resistance of the cable **51** and thus both cables are maintained under tension as long as pressure fluid is supplied to the cylinder. Preferably the pressure fluid for this purpose is derived from the same source as the pressure fluid for operating the reciprocating actuator, that is, the pump **P** so that the tension applied to the cables or traction members is directly proportioned to the force required to reciprocate the head. This is for the reason that the pressure in the hydraulic circuit ordinarily increases in accordance with the resistance offered by the head and this added pressure is effective to increase the tension on the traction members. Smooth and shockless reciprocation of the head is therefore insured under all conditions of operation.

The operation of the pressure fluid actuator and motion transmitting and amplifying mechanism will be readily apparent from the foregoing description. Briefly, the reciprocating part of the actuator, that is the ram **24** and the frame **41** is reciprocated through uniform forward and return strokes by the introduction of pressure fluid alternately into the inner and outer cylinders **21** and **24** of the actuator. The frame is supported and guided in this reciprocation by the rollers **42** and **43**, which roll on rails or bars **44** arranged in the machine base below and generally parallel to the guideway.

The motions of the frame are transmitted to the head through flexible traction members in the form of wire cables **51** and **52**. Upon movement of the ram **24** toward the position shown in Fig. 2, the cable **51** is drawn in over the sheave **54** and the cable **52** is paid out in equal amount so that the head is moved forwardly on the guideway to the position shown in Fig. 1. Upon movement of the ram to the left, the cable **52** is taken up by the roller **43** while the cable **51** is paid out, thus moving the head back to retracted position.

During the operation of the machine the tension device **57** maintains the cables taut and thus prevents any lost motion from slack or loose cables. The flexible character of the traction members also assists in producing the proper motion of the head for precision honing by absorbing any shock or jar at the ends of the reciprocating stroke.

It will be apparent from the foregoing that the invention provides a honing machine of novel and advantageous construction. The machine is provided with novel reciprocating mechanism including a pressure fluid operated actu-

ator of the reciprocatory type and motion transmitting and amplifying mechanism of novel and improved construction capable of effecting smooth shockless relative reciprocation of the honing tool and the work piece. Due to the novel construction of the actuator, the movements of the head or carriage are executed at a uniform rate in both its forward and return strokes.

I claim as my invention:

1. A honing machine having, in combination, an elongated base, a horizontal guideway on said base, a head mounted for reciprocation on said guideway, means for reciprocating said head comprising, a power operated actuator including a reciprocable part, a track disposed within said base below the guideway and extending generally parallel thereto, a roller on said part engageable with the track for supporting and guiding the part in its reciprocation, a rotatable member supported on the base at each end of the guideway, and a pair of flexible traction members anchored to the head and connected respectively to opposite ends of the base, said members each passing over one of said rollers and over the rotatable member at the end of the base to which the member is connected.

2. A honing machine having, in combination, an elongated base, a horizontal guideway on said base, a head mounted for reciprocation on said guideway, means for reciprocating said head comprising, a power operated actuator including a reciprocable part, a pair of elongated bars mounted in the base in spaced parallel relation to define a track extending generally parallel to the guideway, a pair of rollers on said part engageable with said bars to support the part, said rollers having oppositely facing flanges spaced apart to define a peripheral groove around the roller and adapted to cooperate with the bars to guide the part in its reciprocation, a sheave rotatably supported on the base at each end of the guideway, and a pair of flexible cables anchored to the head and connected respectively to op-

posite ends of the base, each of said cables running in the peripheral groove of one of said rollers and over the sheave at the end of the base to which the cable is connected.

3. A honing machine having, in combination, an elongated base, a guideway on said base, a head mounted for reciprocation on said guideway, means for reciprocating said head comprising an actuator having a reciprocable part, pressure fluid operated means for reciprocating said part, means operatively connecting said part with the head including a member rotatably supported on the base at each end of the guideway, roller means rotatably supported on the reciprocating part, a pair of flexible traction members anchored to the head and connected respectively to opposite ends of the base, said members each passing over one of said roller means and over one of said rotatable members, a second pressure fluid operated means acting on one of said traction members to maintain the members under tension, and a common source of pressure fluid for operating both of said pressure fluid means.

4. A honing machine having, in combination, an elongated base, a guideway on said base, a head mounted for reciprocation on said guideway, a cylinder disposed in said base with its axis generally parallel to said guideway, a ram projecting from said cylinder, means for supplying pressure fluid to the cylinder to reciprocate said ram, a frame secured to said ram for reciprocation therewith, rollers journaled on said frame for supporting the frame in its reciprocation, means operatively connecting the head with said frame to reciprocate therewith comprising, a pair of rotatable members supported on the machine base, one at each end of the guideway, and a pair of flexible traction members anchored to the head each passing over one of said rotatable members and one of said rollers.

HARRY J. CALDWELL.
